Thos. S. Winslow.

UNITED STATES PATENT OFFICE.

THOMAS S. WINSLOW, OF NEW YORK, N. Y., ASSIGNOR TO ADELIA E. WINSLOW.

IMPROVEMENT IN MOSQUITO-NETS.

Specification forming part of Letters Patent No. 124,239, dated March 5, 1872; antedated January 26, 1872.

SPECIFICATION.

THOS. S. WINSLOW, of the city and county of New York and State of New York, has invented and produced a new and original Improvement in Mosquito-Net, of which the following is a specification:

Nature and Object of the Invention.

The nature of my invention is a self-sustaining net. The object of the invention is to secure a mosquito-net that is independent of any of the usual support, can be readily put up and down, and removed if necessary; is better arranged for temporary use and for invalids and children than any other net, and particularly adapted for sofa-beds and couches.

Description of the Accompanying Drawing.

A is the frame, of wire or other material, composed of three or more wires bent to the form of an arch, jointed by a rivet at both ends, so as to allow the wires to move freely and independent of each other on the joints or rivets. B is an eye on the outside of each rivet, for the purpose of securing the net to the frame, thereby keeping the net in its place. C is a cord secured to the center of each arch

to keep the wires at their proper distance from each other, and to relieve the net from being strained. D is the net, of lace or other material, cut and shaped to the frame, and being kept in its place by being secured to the eyes of the rivets, as also to the wires of the frame. E is a chain, or other heavy elastic pliable material, attached to the edge of the net, which balances the frame, keeping it in an upright position, as also keeping the net close to irregularities of the bed or object that it may rest upon. F is a joint on the sides of each wire of each arch, for the purpose of disconnecting the arches for packing purposes.

Claims.

1. The chain E or its equivalent, when combined with the net of a mosquito-frame, substantially as and for the purposes set forth.
2. The combination of the frame A, the eye-rivet B, cord C, net D, chain E, and joint F, constructed substantially for the purpose specified.

THOS. S. WINSLOW.

In presence of—

ROBERT H. HUNTER,
JAS. W. HALE.
